CHOW LING SHANG, OF MACAO, CHINA.

CALCULATOR.

SPECIFICATION forming part of Letters Patent No. 654,026, dated July 17, 1900.

Application filed January 29, 1900. Serial No. 3,218. (No model.)

To all whom it may concern:

Be it known that I, CHOW LING SHANG, a subject of the Emperor of China, and a resident of Macao, China, have invented a new and Improved Calculator, of which the following is a full, clear, and exact description.

My invention relates to calculators, particularly to devices for facilitating multiplication and division.

10 The improved device consists of a suitable board or base and a series of movable parts, as strips or tapes, secured thereto and bearing figures in the particular novel arrangement hereinafter described and claimed.

15 Reference is to be had to the accompanying drawings, forming a part of this specification, in which similar characters of reference indicate corresponding parts in all the figures.

Figure 1 is an elevation of my improved 20 calculator. Fig. 2 is a cross-section thereof on the line 2 2 of Fig. 1, and Fig. 3 is a broken view of one of the tapes.

As illustrated, the calculator comprises a base consisting of a board or plate A, made 25 of wood, cardboard, metal, or any other suitable material. To the said base are secured guides B, preferably one at the top and one at the bottom, said guides forming passages for the front run of each of the tapes C, while 30 the rear run of said tapes is allowed to pass loosely behind the base, as shown in Fig. 2. The tapes are preferably endless, as shown, so that they will not be liable to become disconnected from the base, although this is not 35 an absolutely essential feature of my invention. The tapes C are practically alike, except that they carry different designating characters a at their heads. Thus the first tape has the designating character I, the sec-

40 ond tape has the character II, and so on. Each tape is divided longitudinally into two columns and transversely into groups of nine figures each. In the first group, b, all the figures are naughts. In the second group, c, the

45 numbers "1" to "9" appear in their regular sequence in the right-hand column of the tape. In the third group, d, appear the numeral "2" and its multiples up to "18," the units being in the right-hand column and

50 the tens in the left-hand column of the tape. Similarly in the groups e and f appear the

multiples of "3" and "4," and so on throughout the tape until the group g, in which the multiples of nine are contained. After this the numbers "1" to "9" appear in the center of the tape, as at h, the division of the tape into two columns being abandoned at that point. Between the group h and the designating character a a blank space i may be left.

The manner of using the calculator will be understood best by reference to an example. Thus let us assume that the operator wants to find the product eight times eight thousand four hundred and ninety-seven. He then 55 takes the four tapes from the right—that is, the tapes marked I, II, III, IV—and moves them until the numbers "8," "4," "9," "7," respectively, of the said tapes come into the same horizontal line or row, preferably immediately below the upper guide B. The other tapes are left in their normal position, in which the series of numbers of the group h are directly below said upper guide B. Preferably the distance between the two guides 60 is approximately equal to the length of one of the groups h c, &c. Now to find eight times eight thousand four hundred and ninety-seven the operator finds in the eighth line the number "56" on the first tape I, the number "72" on the tape II, the number "32" on the tape III, and the number "64" on the tape IV. He can easily write down the product by writing down for each tape the number contained in the right-hand column there- 65 of, with the addition of the number contained in the left-hand column of the next adjacent tape to the right—that is, the operator will add contiguous numbers on different tapes. Thus he will add "2" and "5" from tapes I 70 and II, "2" and "7" from tapes II and III, and "4" and "3" from tapes III and IV. He will thus get the result, "67,976." From this example the figuring of other products will be readily understood.

In division the improved calculator is employed to readily find multiples of the divisor and to do away with the tedious multiplications, as will be understood best by an example. Suppose it is desired to divide "212,425" 75 by "8,497." This is begun in the usual way by dividing "21,242" by "8,497," giving "2"

as the first figure of the quotient, and the calculator may be utilized for this operation also, since it shows that "21" (in the thousands) is between the double ("16,994") and the triple ("25,491") of "8,497." Twice "8,497" is then read off on the machine as "16,994" and subtracted in the usual way from "21,242," leaving the remainder "4,248." To this remainder is added the last figure, "5," and "42,485" is divided by "8,497." The machine shows at a glance that "42,485" is equal to five times eight thousand four hundred and ninety-seven. The result of the division therefore is "25." The example would be written as follows:

$$\begin{array}{r}
 212425 \div 8497 = 25 \\
 16994 \\
 \hline
 42485
 \end{array}$$

The mental operation would thus be reduced to making the subtraction.

To multiply by a number larger than ten I proceed according to the well-known method of adding the results of partial multiplications. Thus to find two hundred and thirty-four times eight thousand four hundred and ninety-seven the three partial products "2×8,497," "3×8,497," and "4×8,497" are written down as found on the machine, shifting the figures to the right for each successive product, as usual, and adding these partial products. The operation carried out would therefore appear as follows:

$$\begin{array}{r}
 16994 \\
 25491 \\
 33988 \\
 \hline
 1988298
 \end{array}$$

The mental operation would thus be reduced to adding the partial products found on the machine.

It will be observed that the lower portions of the strips or tapes depend loosely from the base or support A, so that they may be readily wrapped around the same, thus facilitating the packing and shipping of the device and enabling it to be readily carried in the pocket.

I desire it to be understood that various modifications may be made without departing from the nature of my invention. Thus I may use more than two guides B, and for the purpose of guiding the eyes of the operator and of preventing mistakes I may make the numbers in different colors alternately—for instance, in black and red.

Having thus described my invention, I

claim as new and desire to secure by Letters Patent—

1. A calculator, comprising a base or support, and a series of independent strips movable side by side on said support and each bearing numerals arranged in groups, one group of each strip being formed by the multiples of "1" (from "1" to "9"), another by the multiples of "2," a third by the multiples of "3," &c.

2. A calculator, comprising a flat base or support, a guide secured thereto, and a series of strips passing through said guide and arranged side by side, each of said strips bearing numerals arranged in groups, one group containing the numbers from "1" to "9," in their regular sequence, the next group the multiples of "2," from "2" to "18," the one following, those of "3," from "3" to "27," &c., the strips, adjacent to the said guide, being adapted to lie on the said flat base so that a portion of each strip, containing a whole group of numerals, will be flat so as to plainly expose to view, at one and the same time, an entire group of numerals on each strip.

3. A calculator, comprising a base or support, and a series of independent strips movable side by side on said support and having their lower portions loosely depending from said support, so that said portions can be wrapped around the support, each strip bearing numerals arranged in groups, one group of each strip being formed by the multiples of "1" (from "1" to "9"), another by the multiples of "2," a third by the multiples of "3," &c.

4. A calculator, comprising a flat base or support, a guide secured thereto, and a series of strips passing through said guide and arranged side by side, each of said strips being divided longitudinally into columns and transversely into groups, one group containing the numbers from "1" to "9," in their regular sequence, the next group the multiples of "2," from "2" to "18," the one following, those of "3," from "3" to "27," &c., the strips, adjacent to the said guide, being adapted to lie on the said flat base so that a portion of each strip, containing a whole group of numerals, will be flat so as to plainly expose to view, at one and the same time, an entire group of numerals on each strip.

In testimony whereof I have signed my name to this specification in the presence of two subscribing witnesses.
